UNITED STATES PATENT OFFICE.

WILLIAM JACOBSEN, JAMES DUNCAN CAMERON, AND FREDERIC JOSEPH LOUGH, OF DUNEDIN, NEW ZEALAND, ASSIGNEES TO THE JACOBSEN DESTINATION INDICATOR COMPANY LIMITED, OF DUNEDIN, NEW ZEALAND, A CORPORATION OF NEW ZEALAND.

STREET AND STATION INDICATOR.

1,135,693.

Specification of Letters Patent.

Patented Apr. 13, 1915.

Application filed December 20, 1912. Serial No. 737,773.

To all whom it may concern:

Be it known that we, WILLIAM JACOBSEN, JAMES DUNCAN CAMERON, and FREDERIC JOSEPH LOUGH, all citizens of the Dominion 5 of New Zealand, and residing at Dunedin, in the Provincial District of Otago, in the Dominion of New Zealand, have invented certain new and useful Improvements in Street and Station Indicators, of which the 10 following is a specification.

This invention relates to apparatus employed to indicate the next stopping place of railway trains and tramcars and the like and is also applicable for employment in 15 connection with the exhibiting of telephone lists, street directories, advertisements and the like.

The invention may be mechanically operated or may be driven by electricity and 20 consists in the improved mechanism now about to be particularly described by the aid of the accompanying drawings of which:—

Figure 1, is an end elevation of a tramcar fitted with the invention. Fig. 2, is an elevation 25 of a casing. Fig. 3, a longitudinal section. Fig. 4, a front end elevation, and Fig. 5, a rear end elevation of the apparatus. Fig. 6, is an elevation of a spring operated reversing pin. Fig. 7, a longitudinal section, and Fig. 8, a cross sectional elevation 30 of a striking finger and mechanism, and Fig. 9, an elevation of a tension.

Referring in the first place more particularly to apparatus which is mechanically operated, a striking plate 1 is fixed above the railway or tramway 2 in a position where it will be struck by a striking finger 3 pivoted by a spindle 4 upon a standard 5 fixed to the vehicle 6. A toothed quadrant 7 fixed 35 to the spindle 4 gears with a pinion 8 mounted upon a spindle 9 to which an arm 10 is fixed. A chain, cord or the like 14, is attached to the arm 10 and provided with a spring tension, as shown in Fig. 9. This 40 tension consists of a bolt 15 provided with a nut 16 and a plate 17, a spring 18 mounted upon the bolt between the nut 16 and the plate 17, and a shackle 19 secured to the plate 17. The other end 20 of the chain or 45 cord is attached to a hook 21 adapted to engage in one of a plurality of holes 24 in a disk 25 having a hole 26 to fit the sided end of a main spindle 30 and kept in position by a nut 31 screwed upon the said spindle.

The spindle 30 is mounted in end plates 32 55 and 33, and a coil spring 34 surrounding the end of the said spindles has one end 35 engaged by the disk 25 and the other end 36 engaged by the end plate 33. The spring is inclosed in a casing 37 of which the disk 60 25 forms an end. The opposite end of the spindle 30 is provided with an arm 40 rigidly fixed to the spindle and in which a pin 41 is pivoted and to which a reversible pawl 42 is fixed. The pin 41 has an arm 43 65 provided with an operating knob 44 and with a stud 45 which is connected to the casing 46 by a tension spring 47 so that when the pawl 42 is thrown over upon either side of the center of the spindle 30 by turning over the knob 44 in the direction shown by the arrow in Fig. 6, the tension spring 47 tends to retain the pawl upon that side to which it has been turned, the movement being limited at a pin 50 projecting from the 70 spindle 30 and contacting with lugs or pins 51 projecting from the plate 32.

The pawl 42 engages a ratchet wheel 55 integral with a toothed wheel 56 mounted freely upon the spindle 30. The wheel 56 80 gears with pinions 57 and 58 fixed to short shafts 60 and 61 mounted in the plate 32. The shaft 61 is provided with an operating handle 62 and the inner ends of the said shafts 60 and 61 receive the ends of roller 85 spindles 63 and 64 and have slots 65 and 66 to engage pins 67 and 68 projecting radially from the spindle 30. The opposite ends 70 and 71 of the spindles 63 and 64 are pointed and pivoted in blocks 72 and 73 slidable in 90 bearings in the plate 33, and projected by springs 74 and 75. A band 76 bearing the names of streets, stations or the like is mounted upon the rollers 78 and 79 fixed to the spindles 63 and 64, the said band 95 passing around a tension roller 80 which is mounted in slots 81 formed in the plates 32 and 33.

When the finger 3 strikes the plate 1 its quadrant 7 operates the pinion 8 and arm 100 10, whereby a pull is exerted upon the cord 14, the hook 21 operates the disk 25, the arm 40 and the pawl 42, the pinions 57 and 58 are rotated by the wheel 56 and the band 76 wrapped either upon the roller 78 or 79 105 according to the way in which the pawl 42 is set. The movement of the spindle 30 by the disk 25 being limited by the pin 50 strik-

ing the stops 51, excess of motion of the finger 3 is absorbed by the tension, shown in Fig. 9. The return stroke of the disk is effected by the spring 34. At the end of the 5 journey, an operator reverses the pawl 42 by means of the operating knob 44, the mechanism will then rewind the band 76 upon the roller from which it had been withdrawn during the previous journey. If the 10 band 76 should require adjusting at any time, this is readily effected by means of the operating handle 62.

What we do claim and desire to secure by Letters Patent of the United States is:—

- 15 1. In an apparatus of the kind described, the combination with an over head wire having a striking plate secured thereto, of a vehicle, a striking finger mounted upon the vehicle adapted to strike against said plate, a quadrant rotatable with the finger, a cord operable by the action of the quadrant, a casing, a main spindle disposed within said casing and rotatable by the pull of the cord, an arm fixed to the spindle, a pin pivoted in the arm, a pawl fixed to the pin, a spring, an arm fixed to the pin and connected to the casing by said spring, a spur wheel, a ratchet wheel operable by said pawl and integral with said spur wheel, pinions gearing with said spur wheel, a pair of rollers, spindles upon which the pinions are fixed and adapted to operate said rollers, and a station indicating band mounted upon said rollers.
- 20 2. In an apparatus of the kind described, the combination with an over head wire having a striking plate secured thereto, of a vehicle, a striking finger mounted upon the vehicle and adapted to contact with said plate, a quadrant rotatable with the finger, a cord operable by the action of the quadrant, a casing, a main spindle disposed within said casing, a disk having a plurality of holes and fixed to the main spindle, a hook 25 upon said cord adapted to engage one of said holes, an arm fixed to the spindle, a pin pivoted in said arm, a pawl fixed to the pin, a spring, an arm fixed to the pin and connected to the casing by said spring, a spur wheel, a ratchet wheel operable by the pawl and integral with said spur wheel, pinions gearing with said spur wheel, a pair of rollers, spindles upon which the pinions are fixed and adapted to operate said rollers, a station indicating band mounted upon said rollers, and a spring surrounding the end of the main spindle and connected at one end to said end plate of the apparatus and at the other end 30 to the disk, a pin projecting from the main spindle, and stops limiting the movement of said pin.
- 35 3. In an apparatus of the kind described, the combination with an overhead wire having a striking plate secured thereto, of a vehicle, a striking finger mounted upon the vehicle and adapted to contact with said plate, a quadrant rotatable with the finger, a cord operable by the action of the quadrant, a casing, a main spindle disposed within said casing, a disk having a plurality of holes and fixed to the main spindle, a hook 40 upon said cord adapted to engage one of said holes, an arm fixed to the spindle, a pin pivoted in said arm, a pawl fixed to the pin, a spring, an arm fixed to the pin and connected to the casing by said spring, a spur wheel, a ratchet wheel operable by the pawl and integral with said spur wheel, pinions gearing with said spur wheel, a pair of rollers, spindles upon which the pinions are fixed and adapted to operate 45 said rollers, and a station indicating band mounted upon said rollers.
- 45 4. In an apparatus of the kind described, the combination with an over head wire having a striking plate secured thereto, of a vehicle, a striking finger mounted upon the vehicle adapted to strike against said plate, a quadrant rotatable with the finger, a cord operable by the action of the quadrant, a casing, a main spindle disposed within said casing and rotatable by the pull of the cord, an end plate and a disk spaced therefrom secured to said main spindle, an arm fixed to the spindle, a pin pivoted in the arm, a pawl fixed to the pin, a spring, an arm fixed to the pin and connected to the casing by said spring, a spur wheel, a ratchet wheel operable by said pawl and integral with said spur wheel, pinions gearing with said spur wheel, a pair of rollers, spindles upon which the pinions are fixed and adapted to operate said rollers, and a station indicating band mounted upon said rollers, as 50 and for the purpose specified.
- 50 5. In an apparatus of the type described, the combination with an over head wire supporting a striking plate secured thereto, of a vehicle, a striking finger mounted upon the vehicle adapted to strike against said plate, a quadrant rotatable with the finger, a cord operable by the action of the quadrant, a casing, a main spindle disposed within said casing and rotatable by the pull of the cord, an end plate and a disk spaced therefrom secured to said main spindle, an arm fixed to the spindle, a pin pivoted in the arm, a pawl fixed to the pin, a spring, an arm fixed to the pin and connected to the casing by said spring, a spur wheel, a ratchet wheel operable by the pawl and integral with said spur wheel, pinions gearing with said spur wheel, a pair of rollers, spindles upon which the pinions are fixed and adapted to operate said rollers, a station indicating band mounted upon said rollers, a spring surrounding the end of the main spindle and connected at one end to said end plate of the apparatus and at the other end 55 to the disk, a pin projecting from the main spindle, and stops limiting the movement of said pin.
- 55 6. In an apparatus of the type described, the combination with an overhead wire having a striking plate secured thereto, of a vehicle, a striking finger mounted upon the vehicle and adapted to contact with said plate, a quadrant rotatable with the finger, a cord operable by the action of the quadrant, a casing, a main spindle disposed within said casing, a disk having a plurality of holes and fixed to the main spindle, a hook 60 upon said cord adapted to engage one of said holes, an arm fixed to the spindle, a pin pivoted in said arm, a pawl fixed to the pin, a spring, an arm fixed to the pin and connected to the casing by said spring, a spur wheel, a ratchet wheel operable by the pawl and integral with said spur wheel, pinions gearing with said spur wheel, a pair of rollers, spindles upon which the pinions are fixed and adapted to operate said rollers, and a station indicating band mounted upon said rollers, and for the purpose specified.

4. In an apparatus of the type described, the combination with an over head wire supporting a striking plate secured thereto, of a vehicle, a striking finger mounted upon the vehicle adapted to strike against said plate, a quadrant rotatable with the finger, a cord operable by the action of the quadrant, a casing, a main spindle disposed within said casing and rotatable by the pull of the cord, an end plate and a disk spaced therefrom secured to said main spindle, an arm fixed to the spindle, a pin pivoted in the arm, a pawl fixed to the pin, a spring, an arm fixed to the pin and connected to the casing by said spring, a spur wheel, a ratchet wheel operable by the pawl and integral with said spur wheel, pinions gearing with said spur wheel, a pair of rollers, spindles upon which the pinions are fixed and adapted to operate said rollers, a station indicating band mounted upon said rollers, a spring surrounding the end of the main spindle and connected at one end to said end plate of the apparatus and at the other end 90 to the disk, a pin projecting from the main spindle, and stops limiting the movement of said pin.

In testimony whereof we have signed our names to this specification in the presence of 110 two witnesses.
